MERCURY SWITCH

Original Filed Aug. 20, 1927

UNITED STATES PATENT OFFICE

PAUL K. CRAMBLETT, OF WESLACO, TEXAS, ASSIGNOR, BY MESNE ASSIGNMENTS, TO MINNEAPOLIS-HONEYWELL REGULATOR COMPANY, OF MINNEAPOLIS, MINNESOTA, A CORPORATION OF DELAWARE

MERCURY SWITCH

Original application filed August 20, 1927, Serial No. 214,373. Divided and this application filed July 30, 1930. Serial No. 471,651.

This invention relates in general to mercury switches and more particularly to that type of mercury switch embodying an outer casing or envelope of soft glass or equivalent material and an inner protective element of arc resisting material organized with the other elements of the switch so as to take the stress and heat of the arc.

The present application is a division of my pending application for mercury switch, filed

August 20, 1927, Serial No. 214,373.

One of the principal objects of the present invention is to provide a mercury switch of this character which is especially designed for high speed operation and consequently adapted for use in a sign flasher to control the operation of the socalled chasing border of an electric sign, although, of course, also capable of use in various other diverse applications.

A further object is to provide a mercury switch having a soft glass outer envelope through which the electrodes are sealed and which has hard glass sleeves so supported and mounted within the soft glass outer envelope as to serve the dual purpose of protecting the soft glass outer envelope from the arcs and of insulating the electrodes with which they are associated from the free body of mercury in the outer envelope when this is desirable during the operation of the switch.

A still further object is to provide a mercury switch of the character referred to in the preceding paragraph and wherein the sleeves are mounted in a novel and effective manner on the seals provided for the electrodes.

Other objects and advantages reside in certain novel features of the construction, arrangement and combination of parts which will be hereinafter more fully described and particularly pointed out in the appended claims, reference being had to the accompanying drawing forming a part of this specification, and in which:

Figure 1 is a view in diametric vertical section showing one switch construction embodying the present invention;

Figure 2 is a view in horizontal section taken on line 2—2 of Figure 1;

Figures 3 and 4 are sectional views similar to Figure 1 and illustrating different types of

mercury switches which may have a novel sleeve mounting as illustrated in Figure 1; and

Figure 5 is a diagrammatic view showing, as an example, one circuit with which the switch shown in Figures 1 and 2 may be employed.

Referring to the drawing and more particularly to Figures 1 and 2, the numeral 1 designates generally a mercury switch including an outer envelope 2 which may be constructed of soft glass. Electrodes 3, 4, 5, 6 and 7 extend in through the base of the envelope 2 and are supported in seals 8 which are constituted by integral inward projections or bosses on the base of the soft glass outer envelope. Sleeves 9 surround the electrodes 3, 4, 5 and 6 and are supported on the seals 8 by annular supporting rings and closures 10 which may be constituted of insulating asbestos cement or of any other suitable material. These rings 10 serve the dual purpose of closing the lower ends of the sleeves 9 and of providing a yieldable support for these sleeves on the seals 8. The sleeves 9 are of hard glass, quartz or the like, and it is to be understood in this connection that in the specification and claims wherever these sleeves are referred to as being of hard glass, other equivalent materials are contemplated.

The hard glass sleeves have a different coefficient of expansion from that of the soft glass outer envelope but the supporting rings 10 have the property of yielding to accommodate or compensate for this difference in expansion thereby preventing cracking or breakage. A body of mercury is contained in the outer soft glass envelope and has portions P filling the wells defined by the sleeves 9 and a free portion F surrounding the outside of the sleeves and constantly immersing the electrode 7 which, as shown in Figure 1, is left exposed, that is, without a sleeve.

As shown in Figure 2, the electrodes 3, 4, 5 and 6 and the wells defined by their sleeves are arranged in a circular series within the outer envelope and are spaced from the center thereof and are located at angular intervals with respect to each other. With a mercury switch of this character if suitable mo-

tion is imparted to the outer envelope the free portion F of the body of mercury may be caused to successfully unite with the portions P of the mercury located in the wells surrounding the electrodes 3, 4, 5 and 6.

5 The novel organization of the sleeves with the electrodes and with the outer soft glass envelope is capable of being embodied in various types of mercury switches.

10 Figure 3 illustrates a mercury switch S having a soft outer glass envelope shaped to provide wells W and W'. Electrodes E and E' extend into the wells through seals 8' similar to the seals 8 shown in Figure 1. Sleeves 9' having inwardly beveled upper ends are mounted on these seals 8' by means of mounting rings of asbestos cement, or the like, designated at 10' and similar to the rings 10 of Figure 1, except that they are somewhat larger to conform to the size of the sleeves 9' and as shown are not only interposed between the sleeves and seals but are also interposed between the sleeves and the electrodes. This switch S also includes an 25 electrode G constantly immersed in a body of mercury designated at B, which, in the open position of the switch, is divided into two portions, one within the sleeve 9' and the other within the envelope S, but outside the sleeve 9'. In the closed position of the 30 switch these two portions of the mercury unite.

35 In Figure 4 a different type of switch S' is illustrated, and, as in the previous instance, has an electrode H extending in through the outer soft glass envelope through a seal 8^a, the seal 8^a also serving as a support for the hard glass sleeve 9^a through the intermediary of a mounting ring 10^a. In this form the body of mercury is designated at B' and the electrode constantly immersed in the free portion of the mercury is shown at G'.

40 The mercury switch illustrated in Figures 1 and 2 is especially designed and adapted for use as a sign flasher and because of its capacity to successfully make and break one, two, three, four or more circuits it may be conveniently employed for controlling the so-called "chasing border" of an electric sign.

45 In use, the switch shown in Figure 1 may have its electrodes 3, 4, 5 and 6, respectively, connected by suitable conductors C with one side of sets of electric lamps designated at 3', 4', 5' and 6'. The opposite sides of the 50 lamps are connected to a wire C' which leads to the negative source of current. The positive source of current is connected by a wire C'' with the electrode 7. The free portion F of the mercury switch is of such quantity 55 with respect to the size of the outer envelope and the spacing of the electrodes as to simultaneously unite with the portions P in three of the wells or sleeves 9 while being spaced from the mercury P in the other well. This 60 may be varied, however, to cause the free por-

65 tions F to unite with the mercury in any desired number of wells. Thus, as illustrated in Figure 5, the mercury F bridges the electrodes 7, 6, 5 and 4. This energizes all of the lamps 6', 5' and 4' but leaves the lamps 3' 70 75 extinguished. As the mercury travels around the envelope it breaks away from the mercury surrounding the electrodes 6, 5, 4 and 3 in the order named, and thus, the lamps are lighted in such an intermittent order as to give the desired chasing effect.

75 The desirable operating motion is imparted to the switch in any suitable manner as, for example, by means fully shown and described in my pending application for mercury 80 switches, filed August 20, 1927, Serial No. 214,373.

85 The switches shown in Figures 3 and 4 may be operated in any suitable manner as by tipping or rocking or in shuttle fashion.

90 It is obvious that the switches shown in Figures 1, 2 and 3 are adapted for pinch or machine sealing inasmuch as the electrodes are sealed in through the envelope or casing of the switch at one end and in spaced relation. Along with this advantage these switches provide the protective elements of 95 arc resistant material which form traps functioning to entrap and confine portions of the mercury while leaving a free portion which unites and divides with the entrapped portions during the operation of the switch.

99 The invention claimed is:

100 1. A mercury switch comprising an outer envelope, an inwardly extending boss carried by the outer envelope, an electrode extending in through the boss, and a sleeve surrounding the electrode and the boss, and yieldable means supporting the sleeve on the boss.

105 2. A mercury switch comprising a casing, spaced electrodes sealed through the casing at one end thereof, a body of mercury in the casing, a separate protective sleeve surrounding one electrode, a yieldable supporting member and closure between one end of the sleeve and the electrode and its seal, said protective sleeve provided with a trap for entrapping and confining a portion of the body of mercury, the remaining free portion of the mercury being adapted to unite with and divide from said entrapped portion upon operation of the switch, said other electrode being constantly immersed in said free portion of the mercury.

110 3. A mercury switch comprising a casing, spaced electrodes sealed through the casing at one end thereof, a body of mercury in the casing, a separate protective element of arc 115 resistant material, yieldable supporting means between one of the electrodes and said protective element, said protective element forming a trap for entrapping and confining a portion of the body of mercury, the remaining free portion of the mercury being adapted to unite with and divide from said en-

trapped portion upon operation of the switch,
one of said electrodes being immersed in the
entrapped portion of the mercury and the
other of said electrodes being immersed in
5 the free portion of the mercury.

5 In witness whereof, I hereto affix my sig-
nature.

PAUL K. CRAMBLETT.
